CLAIM

The ornamental design for a bottle with nozzle, as shown and described.

DESCRIPTION

FIG. 1 is a front, left side, top, perspective view of a bottle with nozzle;

FIG. 2 is a rear view of the bottle with nozzle of FIG. 1;
FIG. 3 is a front view of the bottle with nozzle of FIG. 1;
FIG. 4 is a right side view of the bottle with nozzle of FIG. 1;

FIG. 5 is a left side view of the bottle with nozzle of FIG. 1;

FIG. 6 is a top plan view of the bottle with nozzle of FIG. 1;

FIG. 7 is a bottom plan view of the bottle with nozzle of FIG. 1;

FIG. 8 is a front, left side, top, perspective view of a bottle;

FIG. 9 is a rear view of the bottle of FIG. 8;

FIG. 10 is a front view of the bottle of FIG. 8;

FIG. 11 is a right side view of the bottle of FIG. 8;

FIG. 12 is a left side view of the bottle of FIG. 8;

FIG. 13 is a top plan view of the bottle of FIG. 8;

FIG. 14 is a bottom plan view of the bottle of FIG. 8;

FIG. 15 is a front, left side, top, perspective view of a nozzle;

FIG. 16 is a rear view of the nozzle of FIG. 15;

FIG. 17 is a front view of the nozzle of FIG. 15;

FIG. 18 is a right side view of the nozzle of FIG. 15;

FIG. 19 is a left side view of the nozzle of FIG. 15;

FIG. 20 is a top plan view of the nozzle of FIG. 15; and,

FIG. 21 is a bottom plan view of the nozzle of FIG. 15.
